UNITED STATES PATENT OFFICE.

BENJAMIN TEIPEL, OF COVINGTON, KENTUCKY, ASSIGNOR TO THE LIGOWSKY CLAY PIGEON COMPANY, OF CINCINNATI, OHIO.

TARGET-TRAP.

SPECIFICATION forming part of Letters Patent No. 340,639, dated April 27, 1886.

Application filed January 6, 1886. Serial No. 187,801. (No model.)

To all whom it may concern:

Be it known that I, BENJAMIN TEIPEL, a citizen of the United States, residing at Covington, in the county of Kenton and State of Kentucky, have invented certain new and useful Improvements in Target-Traps, of which the following is a specification.

My improvement relates more particularly to clamps for holding and throwing the glass 10 of artificial targets, of which that known to the trade as the "Ligowsky Clay Pigeon" is a type, and it consists in a novel device for throwing such targets.

In the drawings, Figure 1 is a top view of a 15 throwing-arm and target-clamp embodying my invention, and the secondary position of the free or delivering jaw of the target-holder being indicated by dotted lines. Fig. 2 is a side view of a throwing-arm and target-clamp 20 embodying my invention; Fig. 3, a side view showing a modification of the same; and Figs. 4, 5, and 6 are details.

A represents the throwing-lever or main throwing-arm of a target-trap of any approved 25 construction.

B is the rear or fixed jaw of the target-clamp, having at or near its outer extremity a projection or stop, b. This jaw may be an 30 extension of the arm A, and should be deflected from the line of the main arm in a direction opposite to the line of travel of the delivery-arm in its delivery-sweep, the angle of deflection being preferably less than a right angle.

C is the forward or delivery jaw of the 35 clamp, and is pivoted to the arm A, and provided at or near its outer extremity with a projection or stop, b.

D is a clamping-finger, preferably elastic, 40 secured to the delivery-jaw C.

When the trap is to be used, the jaws B and 45 C are separated sufficiently to admit the target, which is placed in contact with the clamping-finger B, and the delivery-jaw then swung backward until the periphery of the target is in contact with the stops upon both jaws. The fixed jaw serves as a gage for placing the target, and also to hold the target 50 against disengagement from the delivery-jaw by the sudden movement of the throwing-lever when released from the trigger.

In projecting the class of targets to which my invention is especially applicable it is desirable to impart to the target a rapid rotary motion on its vertical axis. This is effected in 55 part by the stress of the clamps D upon the target and in part by the stress of the target upon the stop b on the delivery-jaw. It is desirable that means should be provided for regulating the pressure of the clamp and the 60 resistance of the delivery-jaw. I accomplish this by constructing the spring-clamp with a loop, d, as shown in Fig. 2, and by connecting it with the delivery-jaw by means of the screw-bolt a, which passes through the upper and 65 lower portions of the loop and through the delivery-jaw, serving as a pivot therefor, and takes into a thread in the throwing-arm. By screwing or unscrewing the bolt the pressure of the clamping-finger upon the target and 70 the friction of the delivery-jaw upon the throwing-arm may be increased or diminished at will. The friction of the delivery-jaw upon its bearing may, however, be regulated by means of a coiled spring and bolt, as shown 75 in Fig. 3, or by other suitable means. For the purpose of holding the clamp in position relatively to the delivery-jaw the latter is provided with a lug, c, adapted to take into a corresponding aperture, d', in the spring-clamp. 80

I claim as my invention—

1. A target-clamp consisting of a fixed rear jaw and a pivoted delivery-jaw, both adapted to engage with the periphery of the target, 85 substantially as described.

2. In combination with the throwing-lever of a target-trap, a target-clamp having a fixed rear jaw, a delivery-jaw pivoted to the main throwing-lever, and a spring adapted to regulate the friction of the delivery-jaw upon its bearing, substantially as and for the purpose set forth.

3. A target-clamp consisting of a fixed jaw, a jaw pivoted to the throwing-lever, both 95 adapted to engage with the periphery of the target, and a clamp adapted to hold the target against vertical displacement, substantially as described.

4. A target-clamp consisting of a fixed jaw, 100 a jaw pivoted to the throwing-lever and spring-pressed thereagainst, and a clamp

adapted to hold the target against vertical displacement, substantially as described.

5. A target-clamp consisting of a fixed jaw, a jaw pivoted to the throwing-lever, and a 5 spring-clamp adapted to hold the target against vertical displacement, substantially as described.

6. In combination with the throwing-lever of a target-trap, a target-clamp consisting of 10 a fixed jaw, a jaw pivoted to the throwing-lever, said jaws being provided with stops adapted to engage with the periphery of the target, and a clamp adapted to hold the target against vertical displacement, substantially as described.

15 7. In combination with the throwing-lever of a target-trap, a target-clamp consisting of a fixed jaw, a jaw pivoted to the throwing-le-

ver, and a spring-clamp adapted to hold the target against vertical displacement and to 20 press the pivoted jaw against its bearing, substantially as described.

8. In combination with the throwing-lever of a target-trap, a target-clamp consisting of a fixed jaw, B, a pivoted jaw, C, said jaws being provided with stops b, adapted to engage with the periphery of the target, and a spring-clamp, D d, adapted to hold the target against vertical displacement and to press the pivoted jaw against its bearing, substantially as 25 30 described.

BEN. TEIPEL.
